POSTER DISPLAY FRAME

John Wilson Connell, Mountain View, N. J., assignor to Utility Steel Display Frames, Inc., New York, N. Y., a corporation of New York

Application April 21, 1938, Serial No. 203,248
Renewed December 13, 1939

4 Claims. (Cl. 40—152)

The present invention relates to improvements in poster display frames and its main object is to provide a device of this character which permits posters or display cards to be carried on the side 5 of a wall or a vehicle.

Another object is to provide a water-tight frame that will protect the edges of a display card or poster from rain or snow without the added use of a glass panel front.

10 A further object is to provide a frame designed to allow the advertising poster to be easily and quickly changed and, at the same time, provide means of firmly securing cards or posters, which, at all time, will remain perfectly rigid and will 15 not be subject to changing atmospheric conditions.

Another object of this invention is to provide a frame of this character, whereby, posters printed on water repellent paper may be used in place of 20 the usual cardboard cards, said frame being adapted to stretch the said paper to prevent it from creasing, as well as protecting its edges against weather conditions.

And furthermore, one of the objects is to provide 25 a display frame of simple design and resistant construction, and particularly cheap to manufacture.

It must be herein mentioned that display cards used for out-door display advertising are usually 30 made of cardboard and it has been found that they do not stand up to varying weather conditions. After a card has been lithographed or silk screen processed, it is usual to spray its surface with a light coat of varnish to prevent rain or moisture 35 from penetrating its surface. This, however, does not protect the edges, and as cardboard is composed of a number of layers of paper which vary according to the desired thickness of the card, the edges are, therefor, a vital part of 40 the card which must be protected. If moisture is allowed to penetrate the edges, it splits or causes the layers of paper to separate from one another and thus softens it and causes it to swell and wrinkle and eventually destroy the message it 45 carries.

The invention broadly consists of preferably a stationary frame adapted to be secured to a wall or the side of an automobile or of any vehicle, in which frame is placed a poster or a suitable display card, and of a hingedly secured outer frame 50 adapted to overlap said stationary frame and the edges of said poster or card. Upon said hinged frame is located a circumferential gasket or any suitable strip of resilient material, such as rubber, 55 which is adapted to engage the edges of said post-

er or card when said hinged frame is closed, to form a water-tight joint as well as to fixedly secure said card within said frame, thus protecting its edges from moisture, snow or rain.

In a modification of the present invention is located within said frames a stretching element provided with a rubber gasket co-acting with a longitudinal protuberance provided upon the stationary frame. Said stretching element is disposed on either side of said frame, preferably 10 on the stationary frame, and suitably hinged thereto at one end and so designed as to enable the use of water repellent paper in place of the usual cardboard cards. These elements, together with the rubber gaskets, have for their object to 15 produce a tension (lateral) that will stretch the paper and also serve as a further protection against weather conditions. Wing-nuts are provided upon said elements and are anchored to the frame, being at the same time sufficiently free 20 to turn and thus readily secure the paper sheet in said frame. These stretching elements also serve the purpose of holding the movable or hinged frame when in its open position, to allow 25 the free use of both hands when placing the poster paper in position.

In the drawings:

Figure 1 is a plan view of a frame according to the invention, a portion of the hinged frame being broken away to disclose the stationary frame; 30

Figure 2 is an enlarged cross section view on line 2—2 of Figure 1;

Figure 3 is a segmentary plan view of the stationary frame, (the hinged frame or outer frame not being shown) upon which is mounted the 35 stretching element;

Figure 4 is an enlarged cross section view on line 4—4 of Figure 3, the hinged frame being disclosed;

Figure 5 is a greatly enlarged cross section on 40 line 5—5 of Figure 3, disclosing in detail the stretching element and showing in dotted line the frame which is hinged; and

Figure 6 is an enlarged longitudinal side elevation view of the resilient gasket, broken away 45 at the joint to show the method used to secure the ends together.

Like numerals of reference indicate corresponding parts in each figure.

Referring to the drawings, 1 designates a stationary angle shaped frame adapted to be secured by any suitable means to a wall or to the side of a vehicle (not shown) and 2 is a co-acting channel shaped frame hinged at 3 to the upper end 50 of the frame 1 and adapted to overlap its edges, 55

said frame 2 having adjacent the inner edge of its inner side wall a recess forming a circumferential gasket anchorage in the form of a channel 4 in which the water-tight resilient gasket 5 is mounted. The said gasket is preferably U-shaped and of resilient material such as rubber and has a core 6 of solid rubber. This is the only type of gasket that has been found capable of making a proper water-tight joint between the two frames, as if only solid rubber is used, insufficient resiliency is obtained. The meeting ends of the gasket 5 are preferably tongued and grooved at 7 and 8 and a suitable liquid cement is used to close the joint and make it absolutely watertight.

To secure a poster or a display card (shown only in Figure 5 of the drawings) in the frame, the hinged frame 2 is opened and the card laid into the stationary frame 1. Upon closing the frame 2, the rubber gasket 5 engages the edges of the card or poster and abuts and compresses it against the stationary frame 1 when the said frame 2 is securely locked by means of two or more bolts 9 which extend from the bottom of said stationary frame, said bolts passing through suitable openings located in the hinged frame 2 to be engaged by the nuts 10. Upon tightening said nuts, a constant tension is provided upon the gasket to produce a positive water-tight joint 30 that will prevent moisture or water from reaching the edges of the card.

In the modified form disclosed in Figures 3, 4, and 5, the purpose of which is to permit the use of water repellent paper in place of the usual cardboard poster used, two L-shaped members 11 are located, one at each end of the frame and each is hingedly secured at 12 to the lower portion of the stationary frame 1. Each of said members consist of an inverted U-channel member 13 in which are provided two or more holes 14 adapted to receive the stem 15 of a wing-nut 16 which is anchored therein by means of splitting its stem so as to be loosely secured but sufficiently free to allow the wing-nut to engage the threaded end of the bolt 17 which is preferably welded or otherwise secured upon the said stationary frame 1. In said U-channel member 13 is suitably mounted a longitudinal rubber gasket 18, (female member) co-acting with a longitudinal die stamped protuberance (male member) 19, between which the edge of the sheet of water repellent paper 20 is tightly secured, stretched and held under tension by simply tightening the wing-nut 16. The said members 11 55 may also serve the purpose of a bracket for holding the hinged frame 2 when in its open position.

tion, by resting the said frame upon their ends and thus allowing the free use of both hands when placing the paper poster in position in the frame.

While the invention herein described and illustrated refers to a preferred form of the invention, it should be understood that it is not desired to be limited to this particular construction, as it is evident that its application may be varied in many ways within the scope of the following 10 claims of novelty.

What I claim as my invention is:

1. A poster display frame consisting of a stationary frame, a co-acting frame hinged to said stationary frame and bearing a circumferential 15 gasket channel in which is mounted a resilient gasket, whereby a water tight joint is provided to protect the edges of a card from varying atmospheric conditions, and means to secure said frames together.

2. A poster display frame consisting of a stationary angle shaped frame, a channel shaped frame adapted to overlap said stationary frame and hinged thereto, said hinged frame bearing a resilient circumferential gasket, and means to 25 secure said frames together, whereby the edges of a card mounted in between the said frames will be protected against atmospheric conditions.

3. The combination of a poster display frame and two coacting frames, a stretching element 30 hingedly mounted on each side of one of said frames, said element consisting of a channel shaped member bearing a resilient longitudinal female gasket adapted to register with a co-acting longitudinal male member or protuberance 35 formed upon the other frame, means to secure said gasket over said protuberance, whereby a paper poster will be held in taut and secured position therebetween, and means to secure said frames together.

4. The combination of a poster display frame and two coacting frames bearing intermediate thereof means to provide a water-tight joint, whereby the edges of a paper poster will be protected against varying atmospheric conditions, a 45 stretching element hingedly mounted on each side of one of said frames, said element consisting of a member bearing a female gasket adapted to register with a co-acting male member or protuberance formed upon the other 50 frame, means to secure said gasket to said protuberance, whereby a paper poster may be held taut and in secure position therebetween, and means to secure said frames together.

JOHN W. CONNELL.
